UNITED STATES PATENT OFFICE.

ROBERT HENRY BICKNELL, OF WESTMINSTER, LONDON, ENGLAND.

EXCAVATING APPARATUS.

Application filed July 28, 1925. Serial No. 46,638.

To all whom it may concern:

Be it known that I, ROBERT HENRY BICKNELL, a subject of the King of Great Britain and Ireland, and residing at 23 Old Queen 5 Street, Westminster, London, S. W. 1, England, have invented certain new and useful Improvements in Excavating Apparatus (for which I have filed application in Great Britain, No. 6,388, March 12, 1924), of which the following is a specification.

This invention relates to excavating apparatus designed more particularly for the sinking of vertical or inclined shafts and/or for the boring of tunnels, of the type where- 15 in a tool carrying arm is universally pivoted so as to be capable of operating on any part of the working face, and has for its object to devise simple and robust apparatus of this type whereby the necessary operations 20 may be rapidly and efficiently performed without the use of explosives, the invention thus consisting in improvements in the construction and arrangement of mechanically actuated excavating apparatus.

25 In apparatus of the type to which the invention relates it has been proposed to provide a former limiting movement of the arm so as to control the cross-section of the excavation.

30 The present invention consists in excavating apparatus of the type referred to in which the arm is automatically moved in such a manner as to cause the tool to operate on the whole of the working face.

35 The invention also consists in excavating apparatus of the above character in which the movement of the arm is regulated by a former preferably placed at the back of a spherical or other thrust block at the base 40 of the arm.

The invention also consists in excavating apparatus of the above character particularly designed for shaft sinking in which the excavating or abrading member is fed to its work by gravity by the gradual release 45 of suspension means.

The invention also consists in excavating apparatus of the above character particularly designed for tunnelling in which the excavating or abrading member is fed to its work by hydraulic jacks, screw, or other mechanical means.

50 The invention further consists in excavating apparatus of the character hereinbefore referred to particularly designed for tunnelling having in combination therewith an

intermittently operating shovel or scoop for removing the débris or spoil from the floor of the tunnel adjacent to the working face, such scoop or shovel conveying the material 60 to a band conveyor or other means by which it may be conveyed away from the working face.

The invention further consists in excavating apparatus of the character hereinbefore referred to particularly designed for shaft sinking having suction means for removing the excavated material or spoil from the bottom of the shaft.

The invention still further comprises other 70 details and arrangements hereinafter described or indicated.

The accompanying drawings illustrate more or less diagrammatically two forms of apparatus in accordance with the invention.

Figure 1 is a sectional elevation and

Figure 2 is a plan of parts shown in Figure 1.

Figure 3 is a view on a larger scale showing a part shown in Figure 1 and

Figures 4, 5 and 6 are respectively a side elevation, end elevation and part plan (with parts removed for clearness) of a modified form of apparatus in accordance with the invention.

In carrying my invention into effect in one convenient manner as, for example, when producing an apparatus designed for shaft sinking, I arrange for the whole of the working parts to be carried by a steel or other cylinder or structure *a* of a diameter slightly less than that of the shaft to be sunk and arranged to be aligned and guided in the shaft by means of rollers *b* or other antifriction members engaging the sides of the shaft and capable of being adjusted by suitable means for the purpose of steering or controlling the direction of movement of the apparatus as the sinking proceeds.

The cylinder or structure (hereinafter for brevity termed "the structure") carries an electric motor *c* of suitable type and power arranged to drive the whole of the machinery within the structure (except that required for raising and lowering the structure to or from the surface, lighting, raising the débris and pumping any surplus water from the shaft) and coupled to a two-phase hydro-alternator *d* which produces alternating pressure variations of the required frequency 100 to operate the tool at the end of the traversing arm (as hereinafter referred to) and

of sufficient capacity to avoid the necessity of stopping the electric motor in case of emergencies.

It will be understood that the structure is provided with the necessary girders, brackets, or stiffening means to produce sufficient strength and rigidity in the structure and to support the various working parts carried thereby.

10 There is also a cross bulkhead *e* beneath which is a spherical thrust block *f* in which is mounted the base of an arm *g* (herein referred to as "the traversing arm") which is given a conical motion by means of a former situated above the thrust block and containing a moving member slidably engaging an extension of the traversing arm.

15 The former in the construction illustrated (shown in detail in Figure 3) consists of a cast iron or other rotating disc *h* which may be varied in diameter in accordance with the size or section of the shaft, and on the face of which is a slot *h'* in which is arranged the sliding member *i* with which the extension 20 *g'* of the traversing arm engages, said sliding member being coupled by means of a connecting rod *i'* to a crank *i²* operated by a one-tooth or other timing gear *k', k²*, the former *h* being driven by worm or other gearing from the front end of the hydro-alternator spindle.

25 The wheel *k²* is connected with a toothed wheel *k⁴* meshing with a toothed wheel *k⁴* free on the former shaft and connected with a toothed wheel *k⁵* meshing with a pinion *k⁶* adapted to be rotated by the motor *k⁷*. If wheel *k⁴* is held stationary by the motor, the cross-head *i* will traverse the arm *g* in the direction of the arrow by steps at successive revolutions whereas if the motor rotates the pinion *k⁶* the speed of the traversing movement of the cross-head and the arm *g* will be increased or diminished according to the direction of rotation of the motor *k⁷*.

30 40 45 It is to be observed that by changing the position of the connecting means, namely, the extension *g'* and the cross-head *i* with respect to the axis of the rotatable former and in timed relation with the rotation of the said former that the cross sectional shape of the shaft or tunnel may be varied.

50 55 The traversing arm *g* carries a tool which is preferably removable and which may be of the jack hammer type operated by liquid pressure variations from the hydro-alternator conveyed to the tool through tubes *l, l'* connected flexibly together as by hollow knuckle joints and connected to the interior of the hollow traversing arm *g*.

60 65 The tool hammer is adapted to deliver its blows upon an abrader bit holder *h* which is arranged in a socket at the end of the tool, the front end of the bit holder being preferably conical and being furnished with a number of apertures into which are inserted

the abrader bits *k''* which conveniently consist of short lengths of special steel cut directly from bars.

70 In order to protect the apparatus from reaction due to the very heavy blows upon the abrading tool, I prefer to secure to the thrust block a plurality of radially extending arms *m* which are integral with or rigidly secured to the bulkhead *e* and which carry corrugated or other eccentrically mounted toggle members *m'* or other suitable buffer devices adapted to engage the sides of the shaft or tunnel, the arrangement of arms and toggles being such that the reactive forces caused by the blows of the abraders are almost wholly transmitted through such radial arms to the sides of the shaft or tunnel.

75 80 85 The whole structure with its contained parts is suspended by any suitable means which will permit of its being raised and lowered as required.

90 95 100 105 For the purpose of facilitating the operation of the apparatus I prefer to retain a certain depth of water continually in the bottom of the pit and this also enables me very readily to provide for the removal of the spoil for which purpose I arrange in the upper part of the structure a centrifugal pump *n* or pumps adapted to be driven by suitable means and the suction pipe *n'* of which is carried down through the apparatus and connected to the traversing arm by means of articulated joints *n²*, the mouth of the suction pipe being arranged at the back of the tool so that it always follows the path of the tool and in this way the abraded material and water may together be removed and raised to screens in the upper part of the apparatus, the screens separating the débris from the water so that the latter may be returned to the pit while the débris is raised in skips to the surface.

110 An air duct when necessary is laid to the back of the machine and is connected with an electrically driven exhaust fan placed near the pithead as in deep shafts or when the air is foul it may be necessary to force air down to the machine.

115 Further, in wet shafts any surplus water must be raised by means of pumps erected on the surface and the suction of which is carried down through the machine to a point below the bottom bulkhead.

120 125 130 My improved arrangement of traversing arm may be applied with equal effect and like advantage to tunnelling apparatus with such modifications as may be necessary due to the different direction of operation. Thus, for example, in the case of tunnelling apparatus (an example of which is shown in Figures 4 to 6) I may provide hydraulic jacks *o* fixedly mounted on the shell of the apparatus and fitted with serrated or like toggles *o'* that contact directly with the sides of the tunnel, so that when the ram

is forced backwards the toggles are forced into contact with the sides of the tunnel and the whole apparatus is fed forward, or other means for the purpose of positively feeding the apparatus to its work, with reverse hydraulic rams or other arrangements for withdrawing the apparatus.

Moreover, the structure in the case of tunnelling apparatus is preferably supported on three sets of rollers *p* placed respectively near the front, back and middle of the structure, the fore and aft sets being adjustable for the purpose of steering the apparatus over up or down gradients and with the rollers preferably grooved or corrugated to enable them to pass any silt that may work back or may otherwise be deposited upon the floor of the tunnel.

Additional sets of lateral rollers or the like may also be provided for guiding the apparatus laterally or around curves.

As suction means such as are described in connection with the shaft sinking apparatus will not be suitable for the purpose of removing the débris in the case of a tunnelling apparatus, I provide débris removing means comprising a scoop or shovel *q* which is adapted to operate upon the débris intermittently (being timed for this purpose by suitable means so as not to foul the traversing arm) and to convey the débris to a band conveyor *r* or other means by which it may be conveyed away from the working face, any large pieces of rock or other material that is required to be removed from the working face and that is not suitable for conveyance by the band conveyor being carried by trolleys upon a light tramway that may be laid through the apparatus.

Furthermore, I prefer to provide a fine mesh wire screen (not shown) across the shell near the base of the traversing arm to prevent flying pieces of rock from striking the machine men and in order to prevent rock from the roof falling upon the men the plating *s* of the top of the structure is carried forward to within a reasonably short distance of the working face.

It will be understood that the details of construction hereinbefore given are purely by way of illustration and not of limitation since I may modify the means adopted for mechanically moving the traversing arm or arms so that the arm automatically covers the whole area to be excavated and the various transmission means used in connection with the apparatus, whether mechanical, electrical, hydraulic or pneumatic, may be modified to suit any particular requirements that may have to be fulfilled.

Furthermore, while I have described the use of an abrading tool adapted to be operated upon by a percussive hammer actuated by hydraulic, pneumatic or other

means, it will be clear that I may also vary the form and construction of tool actuating device depending upon the character of the material to be operated upon or any other conditions that may be met with.

The tool also may be operated by gas pressure generated by an internal combustion engine or otherwise in place of the arrangements above referred to.

Having now described my invention, what I claim as new and desire to secure by Letters Patent is:—

1. Excavating apparatus including a tool carrying arm, means situated at a point on the longitudinal axis of the machine for supporting the tool carrying arm for universal movement, rotary driving means, constantly radially moving means connecting the driving means with the tool carrying arm, and means for changing the position of the connecting means with respect to the axis of the driving means to constantly change the position of the arm.

2. Excavating apparatus including a tool carrying arm, means for universally supporting the inner portion of the arm at a point on the longitudinal axis of the machine, rotary driving means, means connecting the driving means with the inner end of the arm, and means for changing the position of the connecting means with respect to the axis of the driving means and in timed relation with the operation of the driving means to consequently change the position of the arm.

3. Excavating apparatus including a tool carrying arm, a thrust block at a point on the longitudinal axis of the machine in which said arm is universally mounted, a rotatable former, means for connecting the inner end of the arm with the former, and timing gear for altering the position of the connecting means with respect to the axis of the former and in timed relation with the rotation of the former to consequently change the position of the arm.

4. Excavating apparatus including a tool carrying arm, a thrust block in which said arm is universally mounted, an extension connected to the arm and projecting rearwardly of the thrust block, a rotary former provided with a transverse groove in its outer surface, a cross-head slidable in said groove and accommodating the extension, a rotatable eccentric connected with the cross-head and operating in the groove, and timing gear for changing the position of the cross-head with respect to the axis of the former during the rotation of the former so that the shape of the section to be excavated may be varied as desired.

In testimony whereof I have signed my name to this specification.
